UNITED STATES PATENT OFFICE.

JAMES W. WILDER, OF BYRON, CALIFORNIA.

SMOKE-CONSUMER.

1,117,614.

Specification of Letters Patent. Patented Nov. 17, 1914.

Application filed June 24, 1914. Serial No. 847,022.

To all whom it may concern:

Be it known that I, JAMES W. WILDER, a citizen of the United States, residing at Byron, in the county of Costa and State of California, have invented new and useful Improvements in Smoke-Consumers, of which the following is a specification.

This invention relates to improvements in furnaces and more particularly to attachments therefor known as smoke consumers.

It is the object of this invention to provide a device adapted for use with any form of furnace in which the smoke caused by the incomplete combustion of the fuel and gases arising therefrom are consumed within the device whereby they are prevented from polluting the atmosphere. The smoke and flue gases are condensed and while such parts as should remain in gaseous form are returned to the fire box the solid particles with the condensing fluid are discharged from the device.

It is further contemplated that the solid residue carried over with the fluid may be reclaimed and put to other uses however such reclaiming of the residue will be made the subject-matter of a separate application.

While the preferred form of this invention is disclosed upon the accompanying sheet of drawing it is to be understood that minor detail changes may be made without departing from the scope thereof.

The figure upon the drawing is a view in central vertical longitudinal section through a device constructed in accordance with this invention with parts shown in side elevation.

In carrying out this invention the size of the relative parts are all proportioned in accordance with the character of the furnace and fire with which it is to be used, and the condensing fluid may be water, air, steam, or any combination of them as the occasion may require. While a smoke consumer constructed in accordance with this invention particularly adapted for use with a steam boiler or battery of boilers is illustrated and described herein, it is to be understood that the applicant reserves the right to make such slight changes as above described to adapt the device to furnaces or fires of a different character without departing from the scope of this invention.

The embodiment of this invention as illustrated comprises a tubular casing 1 to be connected at one end 2 to the furnace flue

(not shown) and closed at the other end 3. While the casing is shown as being supported in a horizontal position it may be supported at an angle or in any desired relation or relative position to the flue of the furnace, the flue terminating at the open end of the casing or being closed therebeyond.

A hollow shaft 4 is mounted centrally of the casing in a bearing 5 supported by the casing at the open end, passes through a central stuffing box 6 upon the closed end, and is supported in a rotatable bearing 7 therebeyond which is provided with a belt 70 pulley 8 or other means for imparting rotation to the shaft exteriorly of the casing.

An outer spaced apart casing or jacket 9 closed at each end is arranged about the entire length of the main casing 1 and is provided with an inlet valve 10 at any convenient point in its walls.

The open or front end 2 of the casing may be of any form or shape beyond the bearing 5 for connection to the flue while the closure of the other end 3 is preferably at right angles to the sides. Commencing adjacent the bearing 5 and extending about two-thirds of the length of the casing is a rotary conveyer 11 of low pitch mounted upon the shaft 4 and a plurality of angular beaters 12 are secured to the shaft throughout the remainder of its length within the casing, the distance between the beater blades 12 preferably being greater than the distance between the convolutions of the conveyer 11.

A plurality of spray nozzles 13 are provided about the hollow shaft 4 between the convolutions of the conveyer 11 and beater blades 12, the distance of the nozzles from each other preferably being greater throughout the beater. A plurality of spray openings 14 are provided about the sides of the casing leading from the jacket and it is preferable that the distances of the openings 100 from each other be greater in the casing surrounding the beater.

A drain valve 15 leading from the bottom of the interior of the main casing 1 is secured upon the end closure which valve is 105 preferably provided with a stem having a star wheel 16 thereon. A gear wheel 17 is secured to rotate with the shaft 4 adjacent the outer side of the end closure meshing with a large gear wheel 18 mounted upon a 110 stud carried by the end closure, having a plurality of star wheel engaging lugs 19,

whereby the valve is continuously opened and closed by the rotation of the shaft.

The inlet valve 10 upon the surrounding jacket is connected to a source of water, air, 5 steam, or such combination of them as may be desired, so that a continuous spray of such fluid is forced through the spray openings in the main casing.

The exterior bearing 7 of the hollow shaft 10 is provided with a tight joint connecting the interior of the shaft 4 to a source of water, air, steam, or such combination of them as may be desired, so that a continuous spray of such fluid is forced through the 15 spray nozzles upon the shaft.

A gas outlet pipe 20 passes through the upper part of the end closure leading from the interior of the main casing to the bottom of a separator 21 from which such gas 20 as may pass over is drawn by the pump 22 and conducted through a pipe 23 therefrom to the fire box (not shown).

The smoke and gases from incomplete combustion are drawn from the flue into the 25 consumer by the rapid rotation of the conveyer on the shaft and as the blades of the conveyer wipe the sides of the casing the smoke and gases are advanced through the sprays from the hollow shaft and casing 30 throughout the length of the conveyer where they are further condensed and mixed by the action of the beaters and sprays, the solid particles settling to the bottom. The automatic operation of the drain valve allows of a successive discharge of the mixed 35 solid particles and fluid while the gas outlet pipe draws off such parts as remain in gaseous state. The latter may return to the fire box and be completely burned. The drain valve may be connected to a waste or sewer 40 or may be connected to a series of settling tanks where the solid particles of the mixture may be reclaimed.

It is therefore seen that all the products 45 of combustion are consumed within this device and none are admitted to the atmosphere.

This device is also adapted for use in connection with smelters and cement works by 50 which the obnoxious gases and dust will be prevented from entering the atmosphere.

What I claim is:

1. In a device of the character described 55 a tubular casing adapted to be connected at one end to the flue of a furnace and closed at the other end, a rotatable shaft centrally mounted within the casing, means to rotate the shaft, means for spraying a fluid within the casing throughout its length, and means

upon the shaft for drawing the flue gases 60 within the casing and mixing with the fluid spray, and an intermittent automatic discharge for the mixed fluid and gas.

2. In a device of the character described, 65 a tubular casing closed at one end, a rotatable hollow shaft centrally mounted therein, a plurality of spray nozzles upon said shaft, means for forcing a fluid therethrough, a spiral conveyer upon the shaft 70 extending inward from the open end, a plurality of angular beaters upon said shaft adjacent the closed end, a fluid jacket surrounding the sides of the casing, and a plurality of spray openings provided in the sides of the casing from said jacket. 75

3. In a device of the character described, 80 a tubular casing closed at one end, a rotatable hollow shaft centrally mounted therein, a plurality of spray nozzles upon said shaft, means for forcing a fluid therethrough, a spiral conveyer upon the shaft extending inward from the open end, a plurality of angular beaters upon said shaft adjacent the 85 closed end, a fluid jacket surrounding the sides of the casing, a plurality of spray openings provided in the sides of the casing from said jacket, a drain valve upon the closed end leading from the bottom of the interior of the casing, means for rotating the shaft, and means operated by the rotation of the shaft to successively open and close the drain valve. 90

4. In a device of the character described, 95 a tubular casing closed at one end, a rotatable hollow shaft centrally mounted therein, a plurality of spray nozzles upon said shaft, means for forcing a fluid therethrough, a spiral conveyer upon the shaft 100 extending inward from the open end, a plurality of angular beaters upon said shaft adjacent the closed end, a fluid jacket surrounding the sides of the casing, a plurality of spray openings provided in the sides of the casing from said jacket, a drain valve upon the closed end leading from the bottom of the interior of the casing, means for rotating the shaft, means operated by the rotation of the shaft to successively open and close the drain valve, a gas outlet pipe 105 in the closed end leading from the top of the interior of the casing into a settling tank, and a gas pipe leading from the settling tank to the fire. 110
